UNITED STATES PATENT OFFICE.

JACOB G. SPANNUTH, OF READING, PENNSYLVANIA, ASSIGNOR OF TWO-THIRDS TO
DODGE & SPANNUTH, OF READING, PENNSYLVANIA.

DESIGN FOR AN AUTOMOBILE REAR-SEAT TOP.

Application filed August 24, 1927. Serial No. 23,190. Term of patent 7 years.

To all whom it may concern:

Be it known that I, JACOB G. SPANNUTH, a citizen of the United States of America, residing in the city of Reading, county of Berks, and State of Pennsylvania, have invented a new, original, and ornamental Design for Automobile Rear-Seat Tops, of which the following is a specification, reference being had to the accompanying drawing, forming a part thereof.

The figures in the drawing are:

Figure 1, a side elevational view of my design.

Figure 2 is a front view thereof.

I claim:

The ornamental design for an automobile rear seat top, as shown.

JACOB G. SPANNUTH.
